Primary Examiner — Philip S Hyder*Assistant Examiner* — Roselynne Cody(74) *Attorney, Agent, or Firm* — Foley & Lardner LLP(57) **CLAIM**

We claim the ornamental design for a pick axe, as shown and described.

DESCRIPTION

FIG. 1 is a front perspective view from above of the claimed design according to one embodiment;

FIG. 2 is a rear perspective view from above of the claimed design of FIG. 1;

FIG. 3 is a front view of the claimed design of FIG. 1;

FIG. 4 is a left side view of the claimed design of FIG. 1;

FIG. 5 is a rear side view of the claimed design of FIG. 1;

FIG. 6 is a right side view of the claimed design of FIG. 1;

FIG. 7 is a top view of the claimed design of FIG. 1;

FIG. 8 is a bottom view of the claimed design of FIG. 1; and,

FIG. 9 is a detail view of a portion of the handle of the claimed design.

Any portion of the article depicted in broken lines forms no part of the claimed design. As shown in FIG. 9, the circular features on the grip of the handle are depicted in broken lines.
